UNITED STATES PATENT OFFICE.

HORACE W. WYMAN, OF WORCESTER, MASSACHUSETTS.

FILLING-REPLENISHING LOOM.

SPECIFICATION forming part of Letters Patent No. 687,470, dated November 26, 1901.

Application filed August 23, 1901. Serial No. 72,990. (No model.)

To all whom it may concern:

Be it known that I, HORACE WINFIELD WYMAN, a citizen of the United States, and a resident of Worcester, county of Worcester, State of Massachusetts, have invented an Improvement in Automatic Filling - Replenishing Looms, of which the following description, in connection with the accompanying drawings, is a specification, like numerals on the drawings representing like parts.

This invention relates more particularly to the so-called "feeler" type of automatic loom, wherein the filling-replenishing is controlled as to its occurrence by or through a feeler, which intermittently feels the filling in the shuttle, means being provided for effecting, through the feeler, the operation of filling-replenishing mechanism before the complete exhaustion of the filling in the shuttle. A loom of this type is shown in United States Patent No. 665,559, granted to me January 8, 1901, wherein a feeler is yieldingly sustained in neutral position to coöperate with the filling in the shuttle, one having a magnetic and the other a magnetized portion, which coöperate upon predetermined exhaustion of the filling to effect filling-replenishing. A very practical and successful arrangement comprises a solenoid-magnet, the core of which constitutes the feeler, the neutral position of the latter being yieldingly maintained by the well-known action of such a magnet upon its core, said magnet being included in and energized by a suitable electric circuit. On alternate beats of the lay the filling in the shuttle engages and moves the feeler in one direction from neutral position, return to the latter being effected by the action of the magnetic field of the coil, the shuttle having movable therewith a metallic body so arranged that magnetomotive action of the feeler in a direction opposite filling-induced movement will be effected when the desired exhaustion of the filling is attained. This movement of the feeler changes it from neutral to active position as the filling-replenishing is effected when the feeler is moved into active position, and one arrangement illustrated in said patent provides for a metallic band upon the filling-carrier in the shuttle, said band being normally covered by the filling. Exhaustion thereof to a predetermined extent exposes the

band and permits the magnetomotive action to take place between the band and the feeler to secure the desired result above referred to. 55 In actual practice I have found it highly desirable to return the feeler to a definite or accurate neutral position after filling-induced movement, so that the filling-engaging portion of the feeler will always start from a fixed 60 point when engaged by the filling, and I have also found it in some cases desirable to prevent premature movement of the feeler into active position, or, in other words, to vary the sensitiveness or responsiveness of the 65 feeler to "magnetomotive action." By the latter term I mean the motion imparted to the feeler by coöperation thereof with a metallic body moving with the shuttle, one being magnetic and the other magnetized to 70 change the feeler from neutral to active position.

My present invention has for its object then means to definitely position the feeler after filling-induced movement thereof and also 75 to vary the sensitiveness of the feeler in accordance with the degree of filling exhaustion required.

Other novel features of my invention will be hereinafter described, and particularly 80 pointed out in the following claims.

In the drawings, Figure 1 is a top or plan view, centrally broken out, of a portion of a feeler-loom having automatic filling-replenishing mechanism with one form of my present invention embodied therein. Fig. 2 is a greatly-enlarged top or plan view of the feeler and the means for controlling it, the feeler being shown in neutral or normal position. Fig. 3 is a right-hand side elevation, also enlarged, of the device shown in Fig. 2. Fig. 4 is an enlarged transverse sectional view on the line $x-x$, Fig. 1, looking toward the left hand. Fig. 5 is an enlarged detail in plan of a portion of the connection including the 95 detector between the actuator for the filling-replenishing mechanism and the feeler.

The loom-frame 1, breast-beam 2, lay 3, having a reed 4, the shuttle-boxes 5 and 6, the latter at the end of the lay adjacent the 100 filling-replenishing mechanism having a slot 7 in its bottom, the picker-sticks 8, the weft or filling fork 9, its slide 10, the knock-off lever 11, moved by the slide to release the

shipper 12 when the filling breaks to stop the loom in usual manner, the cam-shaft 13, having the cam 14 thereon, and the self-threading shuttle 15 may be and are all of well-known or usual construction and substantially as in the patent referred to. The filling-replenishing mechanism shown in Fig. 1 as located at the right-hand side of the loom and comprising, essentially, a hopper or feeder 16 to contain filling-carriers 17 and the transferer 18 to transfer the latter singly to the shuttle at the proper time, the controlling rock-shaft 19, having fast thereon an upturned arm 20, and the weft-hammer 21, vibrated by the cam 14, are also substantially as in said patent, the connections between the rock-shaft 19 and the transferer being omitted for the sake of clearness of illustration and because such connections are old and well known in automatic filling-replenishing looms of the type as, for instance, in United States Patent No. 529,940.

In the structure herein shown each of the filling-carriers 17 is provided with a band or metallic body 22 (see Fig. 1) at the left hand, which band or body is preferably magnetic and located near the base 23 of the filling-carrier, the filling normally covering said metallic body 22 until the filling has been woven off in the operation of the loom to a predetermined extent to expose the said body before complete exhaustion of the filling. The shuttle 15 is provided in one of its side walls with an opening 24, which will be opposite the metallic body 22 when the filling-carrier is in the shuttle, and when the latter is in the outer or left-hand shuttle-box 5 said opening 24 will register with an opening 25 in the front wall 26 of such shuttle-box to permit the entrance into the shuttle of a feeler to feel the filling and to be moved by engagement with the filling on each alternate beat of the lay. As in my Patent No. 665,559 referred to, I herein employ as the feeler a metallic bar or core 27, which is guided and sustained loosely within an insulated coil of wire constituting a solenoid-magnet 28, which is rigidly secured to a stand 29, mounted on the breast-beam of the lay in such position that the feeler will enter the aperture 25 in the shuttle-box 5 at each forward beat of the lay, the solenoid-magnet being included by its terminals 30 and 31 in an electric circuit (not herein shown) to energize the coil. The feeler is longitudinally vibratable or movable in the magnetic field of the coil, the latter constituting means to yieldingly sustain the feeler in neutral or normal position, such position being a defined position under ordinary circumstances; but the feeler can move outward by engagement with the filling in the shuttle, or it may move inwardly under the influence of a magnetic body—such, for instance, as the band 22 on the filling-carrier—and in either case, as in my said patent, when the feeler is released the magnetism exerted by the current in the coil will imme-

diately tend to return the feeler to its neutral position, which may be termed a "balanced" position. The operation of the feeler herein is, broadly, precisely such as is fully described in my said patent, the filling-induced movement of the feeler from neutral position being effected on every alternate beat of the lay until the filling has been exhausted sufficiently to expose the magnetic body 22 moving with the shuttle, and at such time the magnetomotive action between such body and the feeler will cause the latter to be moved rearwardly as the lay recedes to move the feeler from neutral to active position, and by means to be described such active positioning of the feeler is made effective to cause the actuation of the filling-replenishing mechanism.

In actual practice it has been found that the feeler displays a tendency to vibrate back and forth from its neutral position when removed therefrom in a series of strokes of gradually-decreasing amplitude, and when in running the loom at high speed the centering or positioning of the feeler in neutral position after filling-induced movement thereof is interfered with by these vibrations, and I have herein provided means independent of the supporting means for the feeler to return the latter to a definite neutral position, thus preventing the vibration referred to and thereby insuring the position of the filling-contacting portions of the feeler at a fixed point each time it is engaged by filling in the shuttle.

In the present embodiment of my invention the outer end of the feeler is provided with a collar or head 32, and in alignment with the outer end of the feeler I have mounted a slideable plunger 33, mounted in bearings 34, 35 of a stand 36, mounted to rock on a vertical fulcrum 37, adjustably secured to an extension 38 of the supporting-bracket 29, the said fulcrum passing through a slot 39 in said extension and being secured in adjusted position by a suitable check-nut 40. The plunger 33 is provided with a collar 41, which is normally held against the bearing 35 by a spring 42, surrounding the plunger and abutting at its outer end against a hollow screw-stud 43, screwed into the bearing 34, and in which stud the outer end of the plunger 33 is adapted to slide. By means of the stud the tension of the spring will be regulated to increase or decrease the action thereof upon the plunger, and by moving the fulcrum 37 of the swinging stand 36 in or out the bearing 35, which forms a stop for the inward movement of the plunger, is adjusted to determine the inner end of the stroke of the plunger. Now when the feeler is moved outward by engagement with the filling in the shuttle it acts upon the plunger 33 and moves it outward against its spring 42, compressing the latter, so that as the lay goes back the feeler will be retracted by the action of the magnet to its neutral position, and in addi-

tion the spring 42 will expand and will also act upon the feeler through the plunger 33 to retract said feeler to a definite position, and if the momentum of the feeler on such inward movement thereof should be sufficient to carry it a little beyond its exact neutral position then on its return, which of course occurs instantaneously, it will be stopped by striking the inner end of the plunger 33 in the desired definite position. This prevents any of the objectionable vibrational movements to which I have hereinbefore referred and accurately positions the feeler for the next coöperation thereof with the filling. It will be obvious that by the adjustment of the swinging support 36, hereinbefore described, the fixed neutral position of the feeler can be adjusted as may be necessary.

I have also found it desirable in some cases to restrain the feeler from movement from neutral to active position while a considerable quantity of filling remains on the filling-carrier when there is sufficient magnetomotive action between the feeler and the magnetic body on the filling-carrier. It is well known that the interposition of a number of layers of filling between the two metallic bodies 22 and 27 will not act as an insulator against magnetic action, and it is usually desirable that the feeler shall not be moved into active position until it can contact with the metal body movable with the shuttle. I have therefore provided means for restraining or retarding the movement of the feeler under magnetomotive action to accord with the practical surroundings, so that the active positioning of the feeler shall not take place until the predetermined exhaustion of the filling has been effected. One embodiment of such retarding or restraining means is herein shown and comprises a friction-surface 44 on the inner end of the swinging support 36 to bear against one of the sides of the feeler-head 32, the support 36 being acted upon by a plunger 45, sliding through a hollow screw-stud 46, screwed into a sleeve-like support 47 on the bracket or stand 29, a spring 48 being interposed between the head of the plunger 45 and the inner end of the screw-stud 46. Referring to Fig. 2, it will be manifest that the normal action of the spring 48 is to press the friction-surface 44 against the plunger-head 42, and this retarding or frictional action upon the feeler can be regulated by adjusting the screw-stud 46 in or out, a suitable check-nut 49 maintaining the screw-stud in adjusted position. The adjustment is so made that the magnetomotive action will not operate to move the feeler into active position until the practical contact of the feeler and the metallic body moving with the shuttle, the resistance or retardation exerted upon the feeler by means described being sufficient to restrain the feeler from movement into active position until the desired time. This refinement or adjustment of the action of the feeler may be said to vary its sensi-

tiveness or responsiveness to magnetomotive action, and by such refinement of action the extent to which the filling is to be exhausted before effecting the change can be brought down to very fine limits.

Referring to Fig. 2, it will be noted that the swinging support 36 is beyond the friction-surface 44 flared or beveled at 50 away 75 from the feeler, and this is to permit the support 36 to be swung in the direction of the arrow 51, Fig. 2, when the feeler has been moved into active position, withdrawing its head 32 from engagement with the friction-surface 44, such swinging movement of the support 36 being herein made operative to effect the operation of the filling-replenishing mechanism by or through the weft-hammer or actuator 21.

Herein I have dispensed with the rock-shaft 35, arm 34, and finger 37 in my prior patent, and in place of such devices I have pivotally connected at 52 a rod 53 to the swinging support 36, the free end of the rod entering 90 a guideway 54 in an arm 55, (see Figs. 1, 4, and 5,) pivotally connected at 56 with the upper end of the arm 20. The end of the rod 53 which enters the guideway 54 constitutes what may be termed a "detector," as by its 95 abnormal position, which is attained when the detection of the predetermined exhaustion of the filling is effected, it will coöperate with the actuator or weft-hammer. The latter is provided at its upper end with a branch 57, having pivotally connected therewith at 58 a rod 59, which slides back and forth in a guideway 60 in the arm 55, the guideways 54 and 60 intersecting each other and being located substantially at right angles, as clearly shown in 100 Fig. 5, and the rod 59 sustains the arm 55 in position. Now so long as the parts are in normal position, as shown in the drawings, the rod 59 will slide back and forth in the guideway 60 at each vibration of the actuator or weft-hammer 21; but upon movement of the support 36 in the direction of the arrow 51, which takes place when the feeler 27 is inactive, the movement of the rod 53 in the direction of the arrow 51 moves the free end thereof, or 105 the "detector," as I have termed it, into the path of the vibrating rod 59, so that at the next stroke of the latter toward the front of the loom it will move the arm 55 forward to swing outwardly the upturned arm 20 and 110 rock the shaft 19 in the direction of the arrow 61, Fig. 4, to thereby effect through the intervening means the operation of the filling-replenishing mechanism. After the filling has been replenished or changed by the 115 insertion of a fresh supply in the shuttle in the apparatus herein illustrated the next engagement of the filling by the feeler 27 will move the latter outwardly, so that its head 32 will act upon the cam-face 50 and swing 120 the support 36 to the left, viewing Figs. 1 and 2, into normal position, to thereby reset the parts and at the same time withdrawing the detector end of the rod 53 from engagement 125 130

with the vibrating actuator. Lugs or stops 62 63 on the stand 29 serve to limit the swinging movement of the support 36.

It will be manifest that the device for returning the feeler to a definite neutral position after filling-induced movement thereof and also the device for varying the sensitivity or responsiveness of the feeler may be used with equal effect should the feeler be 10 yieldedly maintained in neutral position by oppositely-acting centering-springs, as shown in the modification in my patent referred to.

I have herein shown one practical embodiment of my invention without attempting to 15 describe or illustrate various changes or modifications which may be made by those skilled in the art without departing from the spirit and scope of my invention.

Having fully described my invention, what 20 I claim as new, and desire to secure by Letters Patent, is—

1. In a loom provided with filling-replenishing mechanism, a shuttle adapted to contain a supply of filling, a feeler intermittently engaged and moved from neutral position by the filling in the shuttle, means to yieldedly sustain the feeler in neutral position, a device to independently effect return of the feeler to definite neutral position after filling-induced movement thereof, and magnetically-operating means to move the feeler from neutral to active position upon predetermined exhaustion of the filling, to thereby effect the operation of the filling-replenishing mechanism.

35 2. In a loom provided with filling-replenishing mechanism, a shuttle adapted to contain a supply of filling, a feeler intermittently engaged and moved from neutral position by the filling in the shuttle, means to yieldedly sustain the feeler in neutral position, an adjustable device to independently effect return of the feeler to definite neutral position after filling-induced movement thereof, and magnetically-operating means to move the feeler from neutral to active position upon predetermined exhaustion of the filling, to thereby effect the operation of the filling-replenishing mechanism.

45 3. In a loom provided with filling-replenishing mechanism, a shuttle adapted to contain a supply of filling, a feeler intermittently engaged and moved from neutral position by the filling in the shuttle, means to yieldedly sustain the feeler in neutral position, a retracting device having a fixed stroke, to independently effect return of the feeler to neutral position after filling-induced movement thereof, and magnetically-operating means to move the feeler from neutral to active position upon predetermined exhaustion of the filling, to thereby effect the operation of the filling-replenishing mechanism.

55 4. In a loom provided with filling-replenishing mechanism, a shuttle adapted to contain a supply of filling, a longitudinally-vibratable feeler to intermittently engage and be moved by the filling from neutral position,

means to yieldedly sustain the feeler in neutral position, a spring independent of said means to effect return of the feeler to such 70 position after filling-induced movement thereof, and magnetomotive means, operative upon predetermined exhaustion of the filling, to move the feeler from neutral position and thereby effect the operation of the filling-replenishing mechanism.

5. In a loom provided with filling-replenishing mechanism, a shuttle adapted to contain a supply of filling, a longitudinally-vibratable feeler to intermittently engage and 80 be moved by the filling from neutral position, means to yieldedly sustain the feeler in neutral position, a sliding retracting device to act upon and effect return of the feeler to neutral position after filling-induced movement thereof, a spring to actuate the said device, an adjustable stop to determine the length of the active stroke of the latter, and magnetomotive means to move the feeler from neutral into active position upon exhaustion 95 of the filling to a predetermined extent, to thereby effect the operation of the filling-replenishing mechanism.

6. In a loom provided with filling-replenishing mechanism, a shuttle adapted to contain a supply of filling, a feeler intermittently engaged and moved from neutral position by the filling in the shuttle, means to yieldedly sustain the feeler in neutral position, a spring independent of such means, to effect return 100 of the feeler to neutral position after filling-induced movement thereof, means to vary the tension of the spring, and magnetomotive means, operative upon predetermined exhaustion of the filling, to move the feeler from 105 neutral to active position, to thereby effect the operation of the filling-replenishing mechanism.

7. In a loom provided with filling-replenishing mechanism, a shuttle adapted to contain a supply of filling, a feeler to be intermittently engaged by the filling and moved thereby from neutral position, means to yieldedly sustain the feeler in neutral position and to return it to such position when moved 115 therefrom, magnetomotive means to effect movement of the feeler from neutral to active position upon predetermined exhaustion of the filling, to thereby effect the operation of the filling-replenishing mechanism, and 120 means to vary the responsiveness of the feeler to magnetomotive action.

8. In a loom provided with filling-replenishing mechanism, a shuttle adapted to contain a supply of filling, a feeler to be intermittently engaged by the filling, and moved thereby from neutral position, means to yieldedly sustain the feeler in neutral position and to return it to such position when moved 125 therefrom, magnetomotive means to effect movement of the feeler from neutral to active position upon predetermined exhaustion of the filling, to thereby effect the operation of the filling-replenishing mechanism, and means

to interpose a variable resistance to the movement of the feeler due to such magnetomotive action.

9. In a loom provided with filling-replenishing mechanism, a shuttle adapted to contain a supply of filling, a feeler to be intermittently engaged by the filling and moved thereby from neutral position, means to yieldingly sustain the feeler in neutral position and to return it to such position when moved therefrom, magnetomotive means to effect movement of the feeler from neutral to active position upon predetermined exhaustion of the filling, to thereby effect the operation of the filling-replenishing mechanism, and means to restrain to a variable degree the movement of the feeler from neutral to active position.

10. In a loom provided with filling-replenishing mechanism, a shuttle adapted to contain a supply of filling, a feeler to be intermittently engaged by the filling and moved thereby from neutral position, means to yieldingly sustain the feeler in neutral position and to return it to such position when moved therefrom, magnetomotive means to effect movement of the feeler from neutral to active position upon predetermined exhaustion of the filling, to thereby effect the operation of the filling-replenishing mechanism, an independent device to return the feeler to neutral position after filling-induced movement thereof, and means to vary the responsiveness of the feeler to magnetomotive action.

11. In a loom provided with filling-replenishing mechanism, a shuttle adapted to contain a supply of filling, a feeler to be intermittently engaged by the filling, and moved thereby from neutral position, means to yieldingly sustain the feeler in neutral position and to return it to such position when moved therefrom, magnetomotive means to effect movement of the feeler from neutral to active position upon predetermined exhaustion of the filling, to thereby effect the operation of the filling-replenishing mechanism, an independently-acting spring to return the feeler to neutral position after filling-induced movement thereof, and means to restrain to a variable degree the movement of the feeler from neutral to active position.

12. In a loom provided with filling-replenishing mechanism, a shuttle adapted to contain a supply of filling, a feeler to be intermittently engaged by the filling and moved thereby from neutral position, one being provided with a magnetic and the other with a magnetized portion, means to yieldingly sustain the feeler in neutral position and to return it thereto when moved therefrom, and a spring independent of said means, to effect definite return of the feeler after filling-induced movement thereof, magnetomotive movement of the feeler into active position due to exhaustion of the filling to a predetermined extent effecting the operation of the filling-replenishing mechanism.

13. In a loom, a shuttle adapted to contain

a supply of filling, a yieldingly-sustained feeler capable of being moved with the shuttle by magnetic action from its normal neutral position into active position when by or through a definite exhaustion of the filling in the shuttle a fresh supply is required, filling-supplying mechanism operated by movement of the feeler into active position, and means to retard such movement of the feeler in accordance with the desired degree of filling exhaustion.

14. In a loom, a shuttle adapted to contain a supply of filling, and a magnetic body movable with the shuttle, a solenoid-magnet containing a magnetized core constituting a filling-feeler and balanced in neutral position in said solenoid-magnet, the feeler being moved from neutral to active position by co-operation with the magnetic body upon a predetermined exhaustion of the filling in the shuttle, filling-replenishing mechanism operated by active positioning of the feeler, and an adjustable friction device to normally co-operate with the feeler and prevent premature movement thereof into active position.

15. In a loom, a shuttle adapted to contain a supply of filling, and a magnetic body movable with the shuttle, a solenoid-magnet containing a magnetized core constituting a filling-feeler and balanced in neutral position in said solenoid-magnet, the feeler being moved from neutral to active position by co-operation with the magnetic body upon a predetermined exhaustion of the filling in the shuttle, filling-replenishing mechanism operated by active positioning of the feeler, a friction device to normally co-operate with and prevent premature movement of the feeler into active position, and yielding means independent of the solenoid-magnet to return the feeler to neutral position after filling-induced movement thereof.

16. In a loom, a shuttle having a filling-carrier provided with a magnetic body normally covered by filling, combined with a movable magnetized body adapted to be moved in one direction by engagement with the filling on the filling-carrier, and oppositely movable when said magnetic body is exposed by exhaustion of the filling to a predetermined extent, and means to prevent premature magnetomotive displacement of the feeler.

17. In a loom, a shuttle having a filling-carrier provided with a magnetic body normally covered by filling, combined with a movable magnetized body adapted to be moved in one direction by engagement with the filling on the filling-carrier, and oppositely movable when said magnetic body is exposed by exhaustion of the filling to a predetermined extent, independent main and auxiliary means to return the feeler to definite neutral position after filling-induced movement thereof, and means to normally co-operate with the feeler and prevent premature movement thereof due to magnetomotive action.

18. In a loom provided with filling-replen-

ishing mechanism, a shuttle adapted to contain a supply of filling, and a magnetic body movable therewith, combined with a movable magnetized body adapted to be moved in one direction by engagement with the filling in the shuttle, and oppositely movable by coöperation with said magnetic body upon exhaustion of the filling to a predetermined extent, a retarding device to coöperate with said magnetized body, and to prevent premature movement thereof due to magnetomotive action, a vibrating actuator for the filling-replenishing mechanism, and a detector maintained out of the path of movement of said actuator by said retarding device until the feeler is moved into active position.

19. In a loom provided with filling-replenishing mechanism, a shuttle having a filling-carrier provided with a magnetic body normally covered by filling, combined with a movable magnetized body adapted to be moved in one direction by the filling on the filling-carrier, and movable in the opposite direction by or through coöperation with the magnetic body of the filling-carrier when the latter is exhausted by a predetermined exhaustion of the filling, a spring-operated retarding device to prevent premature magnetomotive action of the feeler, a vibrating actuator for the filling-replenishing mechanism, and a detector operatively connected with the retarding device and moved thereby into engagement with said actuator when movement of the feeler into active position releases the retarding device.

20. In a loom provided with filling-replenishing mechanism, means to control the time of operation thereof including a solenoid-magnet containing a magnetized core constituting a feeler, and balanced in neutral position in and by said magnet, a shuttle provided with a filling-carrier having a magnetic body normally covered by filling, the feeler being moved into active position by exposure of the magnetic body due to exhaustion of filling to a predetermined extent, to thereupon coöperate with the feeler, a swinging support hav-

ing a friction-shoe thereon, a spring to normally press the shoe against the feeler to prevent premature movement thereof into active position, a retracting spring-actuated plunger slidably mounted on said swinging support and adapted to return the feeler to neutral position after filling-induced movement thereof, a stop to limit the stroke of said retracting device, an actuator for the filling-replenishing mechanism, and means movable into position to operate with said actuator by or through swinging movement of said support, to thereby effect the operation of the filling-replenishing mechanism.

21. In a loom provided with filling-replenishing mechanism, means, including a detector, to control its operation, a vibrating actuator adapted to coöperate with the detector to effect the actuation of said means, a shuttle to contain a supply of filling, and a yielding-sustained feeler to intermittently engage the filling in the shuttle, said feeler governing the detector and preventing its coöperation with the actuator until predetermined exhaustion of the filling.

22. In a loom provided with filling-replenishing mechanism controlling means therefor, including a rock-shaft having an attached rocker-arm, a guide-arm pivotally mounted on the rocker-arm, and a detector movable in said guide-arm; a vibrating actuator movable in the latter transversely to the detector, to at times coöperate with the latter and move the guide-arm to turn the rock-shaft, a shuttle to contain a supply of filling, and a yielding-sustained feeler to intermittently engage the filling in the shuttle, the feeler governing the detector and preventing its movement into the path of the actuator until predetermined exhaustion of the filling.

In testimony whereof I have signed my name to this specification in the presence of two subscribing witnesses.

HORACE W. WYMAN.
